Primary Examiner — Christian P. McLean(74) *Attorney, Agent, or Firm* — Arent Fox LLP(57) **CLAIM**

The ornamental design for a rear bumper, as shown and described.

DESCRIPTION

FIG. 1 is a top right perspective view of a rear bumper showing our new design;

FIG. 2 is a top left perspective view of the design shown in FIG. 1;

FIG. 3 is a bottom left perspective view of the design shown in FIG. 1;

FIG. 4 is a bottom right perspective view of the design shown in FIG. 1;

FIG. 5 is a front view of the design shown in FIG. 1;

FIG. 6 is a rear view of the design shown in FIG. 1;

FIG. 7 is a left side view of the design shown in FIG. 1;

FIG. 8 is a right side view of the design shown in FIG. 1;

FIG. 9 is a top view of the design shown in FIG. 1; and,

FIG. 10 is a bottom view of the design shown in FIG. 1.
